HYDRAULIC DUPLICATING MECHANISM FOR MACHINE TOOLS AND THE LIKE

Max Goodrich, Holt, Mich.

Application August 27, 1953, Serial No. 382,535

10 Claims. (Cl. 251—3)

The present invention relates to improvements in hydraulic duplicators attachable to such machine tools as vertical mills, boring mills, lathes, planers, shapers, and the like for controlling the movement of the tool.

Devices of the type to which the present invention pertains are well known commercially and a great many noncommercial proposals pertaining to such devices appear in the patented art.

In general, they are all designed to perform a similar function, namely, that of tracing a master pattern, mold, template or die and in so doing manipulate the cutting tool to duplicate the form of the traced element to close tolerances.

While the basic principles of the present invention are well known, my improved duplicator attachment embodies certain structural refinements and arrangements which have materially obviated chatter when performing extremely fine work and which permits the practical manufacture of an attachment of high precision performance.

Thus, an object of the invention is to provide an improved hydraulic tracer unit so designed that the sensitivity of the tracer finger to all changes in contour of the master template, or the like, is transferred to the valve mechanism which controls the manipulating fluid in such a manner that the sensitivity of the tracer finger thus transferred is undiminished, unretarded and in direct proportion.

Another object is to provide novel structural arrangement in devices of the type described for obviating the tendency toward chatter in the performance of extremely fine duplication.

Another object of the invention is to provide a tracer unit having the control valve so designed that it may be conveniently machined with extreme accuracy.

A further object of the invention resides in a novel arrangement for controlling the free movement of the tracer stem.

A still further object resides in the structural arrangement for transferring to the fluid control valve with great accuracy both axial and lateral deflection of the tracer finger and stem.

A further object is to provide a conveniently located regulator for actuating the control valve whereby the operator may bring the tool into contact with the work with extreme care.

These and other objects and advantages of the present invention residing in the combination, construction and arrangement of the component parts will appear from the following specification and the appended claims.

In the drawings,

Fig. 1 is a perspective view of a vertical milling machine equipped with my improved duplicator attachment,

Fig. 2 is a perspective view of the tracer and control valve unit shown in its mounting structure,

Fig. 3 is a vertical cross-sectional view of the tracer and control valve unit shown in Fig. 2,

Fig. 4 is an exploded perspective view of the sectional structure of the control valve,

Fig. 5 is a detail of the connection between the valve and stem structure,

5 Fig. 6 is a view similar to Fig. 3 taken through the ports of the dampening structure,

Fig. 7 is a top view of Fig. 3, and

Fig. 8 is a detail of the structure for maintaining the valve chamber full of oil.

10 As shown in Figs. 1 and 2, the duplicator attachment 10 is carried upon suitable cross slide structure 12 attached to the vertically movable spindle structure of the milling machine 14 so as to follow the movement of the tool 16. Adjustment of the attachment 10 in a horizontal plane is provided to align the tracer finger 18 with the tool 16 as well as with the template 20 mounted on a bracket 22 to move with the table 24 upon which the work 26 to be machined is carried.

15 The carriage structure 28 of the attachment 10 comprises a lower split bushing portion 30 in which the tracer stem housing 32 is vertically slidable. A suitable attachment bolt 34 having a handle 36 is provided for clamping the split sleeve 30 upon the housing 32 following vertical adjustment. As shown, the housing 32 has an extremely threaded surface 38 to receive the adjustment nut 40 in position for rotation between the upper surface 42 of the sleeve 30 and the lower surface 44 of the thrust plate 46 attached at 48 to the carrier 28. A surface of the nut 40 may have graduations marked thereon to aid in the vertical adjustment of the housing 32 upon manual rotation of the adjustment nut 40.

20 Referring to Fig. 3, the tracer finger 18 is held in the stem 52 by a clamp screw 54. With the finger 18 out of contact with the template 20 the stem 52 is vertically supported by the stem holder 56 which takes the form of an externally threaded bushing screwed into the internally threaded counterbored lower end 58 of the stem housing 32. To remove all slack between this threaded connection, a spring 60 is inserted between the upper end of the stem holder 56 and the shoulder 62; the spring 60 being sufficiently strong as to prevent any side movement between the threaded connection when there is side pressure on the tracer finger 18.

25 Referring to Fig. 3, the tracer finger 18 is held in the stem 52 by a clamp screw 54. With the finger 18 out of contact with the template 20 the stem 52 is vertically supported by the stem holder 56 which takes the form of an externally threaded bushing screwed into the internally threaded counterbored lower end 58 of the stem housing 32. To remove all slack between this threaded connection, a spring 60 is inserted between the upper end of the stem holder 56 and the shoulder 62; the spring 60 being sufficiently strong as to prevent any side movement between the threaded connection when there is side pressure on the tracer finger 18.

30 The stem 52 has a concentric slightly enlarged cylindrical portion 64 which is provided with an extremely close sliding fit within a narrow annular surface constituting what is characterized herein as an annular fulcrum 66; in practice the clearance between the sliding parts constituting the sliding fit being in the order of .0002". Adjacent and below the annular fulcrum 66 is a conical seat portion 68 upon which the lower edge 70 of the cylindrical portion 64 is attached to engage to support the stem 52; the seat portion 68 being disposed at 90° to a radial line between a point of contact between the edge 70 and the seat portion 68 and the point of intersection of the longitudinal axis of the cylindrical portion 64 with a medial plane through the annular fulcrum 66.

35 The axial extent of that portion of the annular fulcrum 66 which forms the .0002" sliding fit with the cylindrical portion 64 is in the order of $\frac{1}{16}$ ". With this narrow bearing and with .0002" clearance, side movement in all directions may take place at the lower end of the tracer finger 18 to the order of $\frac{1}{16}$ " with the tracer finger of usual length, namely, in the order of 3" to 5" below the fulcrum 66. With the seat portion 68 located and constructed as above described, only slight movement of the edge 70 will take place on the seat 68 and such movement will not produce any appreciable upward camming movement to the stem 52. Clearance is provided at 72

40 between the lower end 56 and the stem 52 to accommo-

date the side movement of the finger 18 in all directions. The stem 52 is extended a substantial distance above the fulcrum 66, preferably a distance approximating the distance to the lower end of the finger 18 to provide the upper end 74 and the annular ball seat 76 with approximately the same amount of side movement as may take place at the lower end of the tracer finger 18.

To transfer both axial and lateral movement of the stem 52 to the sectional valve shown in Fig. 3, a ball 78 rests upon the seat 76 and reacts against a similar annular seat 80 defined in the externally threaded pin abutment member 82 which is also the inner race of the ball bearing structure 84. The outer race for the bearing 84 takes the form of a sleeve 86 pressed into a counterbore at the upper end of the stem housing 32. Retaining rings 88 hold the bearings 84 positioned. Below the inner race portion of the member 82 is a threaded portion 89 to which a tubular guide 90 for the inner race is threaded. At the lower end of the guide 90 is a bushing 92 having a sliding fit on the stem 52 at a point adjacent the annular fulcrum 66 so any deflection of the bushing 92 upon side movement of the finger 18 will be extremely small and unappreciable at the upper end in the plane of the bearing 84. Thus, it will become apparent that the member 82 is supported in the stem 32 only for vertical movement to be imparted thereto by the ball 78 by both axial and lateral movement of the seat 76.

To attach the stem 32 to the main valve body 94, the upper end of the stem 32 is threaded to the plate 96 which in turn is piloted upon the valve end plate 98 and attached to the body 10 by screws 100. Hardened bushings 102 and 104 are pressed into a central opening 106 in the plate 98 and shaped to provide an oil chamber 108.

Pin 110 rides on the top of the member 82 with a close sliding fit which permits very little oil to pass by yet the pin 110 is freely slideable in the bushings 102 and 104. At its upper end, the pin 110 abuts a metallic washer 112 and acts, through a resilient cushion or pad 114, preferably of synthetic rubber, upon the push rod 116. The lower threaded end of the rod 116 receives a socket 117 which holds the cushion 114 between the lower end of the rod 116 and the washer 112. The lock nut 118 holds the socket 117 in position.

The adjustable connection between the upper threaded end of the rod 116 and the valve spool 120, best shown in Fig. 5, comprises an internally threaded sleeve 122 having an annular flange 124. To expand the upper end of the rod 116 to lock it to the sleeve 122, the rod 116 is first drilled to one depth by a small drill, then to a lesser depth with a larger drill. The larger hole is then tapped and the end of the rod 116 is slotted at 116' at right angles beyond the depth of the small drill. Thus, when the rod 116 is held against rotation by a suitable wrench engaging the slots, the pointed end of the set screw 126 may be rotated and advanced to engage the shoulder 116" formed between the holes of different diameter to expand the externally threaded slotted end of the rod 116 into locking engagement with the internal threads of the sleeve 122. At the upper end the valve spool 120 is counterbored at 128 to receive the flange 124 of the sleeve 122. An annular groove 130 in the counterbore 128 receives a two-piece locking ring 132. Piloted upon the sleeve 122 is a slideable collar 134 having a radial flange portion 136 to provide a seat for the spring 138 and a thin cylindrical lower end portion 140 of slightly lesser diameter than the lock ring 132 to hold the same in its groove 130 to lock the sleeve 122 to the spool 120.

From this it should appear that the spring 138 acts downwardly on the valve spool 120 indirectly through the collar 134 and flange 124 while the rod 116 acts upwardly on the valve spool 120 through the flange 124 and the lock ring 132. By adjusting the sleeve 122 along the rod 116, the position of the valve spool 120 relative to its fixed ports may be adjusted. This may be accom-

plished by removing the threaded cap 142. A plunger 144 against which the spring 138 abuts at its upper end has a manual push rod 146 which may be depressed to build up the compression upon the spring 138 should the valve spool 120 become stuck in its raised position.

The four-way valve construction for selectively directing the hydraulic fluid to opposite ends of the cylinder 148 attached to the spindle structure functions in a well known manner. Movable valve spool 120 is provided with lands 150 which are machined with great accuracy as to width, spacing and diameter. To provide corresponding accuracy of construction in the fixed ported structure of the valve, the sectional construction of Fig. 4 is stacked within the main through bore 152 and comprises an upper section 154, an intermediate section 156 and a lower section 158. Between these sections are spacer port rings 160 and 162 which are milled to provide radial ports 164 defined between radial teeth 166 with the surface 168 between the teeth 166 being inclined. This arrangement provides the spacer rings 160 and 162 with maximum strength. Also, the rings 160 and 162 may be ground on opposite sides to control their thickness with great accuracy as well as the thickness of the annular port areas 170 between the surface of the sections 154, 156 and 158 spaced by the rings 160 and 162 and regulated by the lands 150.

It will be understood that the end surface of each section 154, 156 and 158 are conveniently ground parallel and the over all length readily held to extreme accuracy. Thus, the structure of Fig. 4 when stacked within the bore 152 will have its over all length accurately held and the port areas 170 will be accurately located with respect to each other as well as with respect to the lands 150. A cap 172 bolted to the body 94 locates the fixed valve structure of Fig. 4 between the bottom plate 98 and the shoulder 174. The cap 142 is threaded into the cap 172 and provided with a gasket at 174 and an O-ring 176 to enable the oil to be sealed within the chamber in which the valve spool 120 is disposed; the pin 110 and its bushings 102 and 104 seal the valve chamber from below.

The fluid flow path through the valve is that of conventional four way valves of the spool type. The intake pressure fluid entering connection 184, Fig. 3, is conducted by an appropriate passageway in body 94 to the ports of section 156 and depending on the direction of movement of lands 150 will either flow into chamber 187 or 189 through the port areas 170. Chambers 187 and 189 are in communication with cylinder connections 188 and 190, respectively, by means of passageways formed in body 94, not shown, and the ports of sections 154 and 158 will provide communication with the exhaust passageway of connection 186 whereby communication of connection 188 with the pressure fluid opens 190 to the exhaust and vice versa to move the cylinders 148 in the desired direction.

Referring to Fig. 6, the structure is shown for controlling valve chatter which has a tendency to develop when the widths of the lands 150 are only in the order of .002" wider than the port area 170 as is done when extremely fine duplication is desired. Any tendency for the valve spool 120 to vibrate or chatter is overcome by maintaining the valve chamber full of oil and metering the oil between opposite ends of the valve chamber between passages 178 and 180 regulated by the adjustable needle valve 182. In this manner, the rate of movement of the valve spool 120 is controlled by the flow of oil past the needle valve 182.

It will be apparent that the oil check arrangement shown in Fig. 6 is dependent upon maintaining of oil in the valve chamber. Referring to Fig. 7, the cap 172 of Fig. 3 is shown in plan view with the oil pressure inlet connection at 184, the oil pressure exhaust connection at 186 and the oil pressure connections leading to opposite ends of the cylinder 148 being indicated at 188 and 190.

To conduct oil from the connection 184 a horizontal passage 192 opens into the lower end of the vertical threaded hole 194. An inclined passage 196 extends from adjacent the upper end of the hole 194 into the central opening 198 in the cap 172 which defines the upper portion of the valve chamber.

A screw 200 having a gasket 202 beneath its head is threaded into the hole 194 to regulate the flow of oil in the passages 192 and 196; the oil under pressure seeping along the spiral clearance between the threads of the hole 194 and the threads of the screw 200, the clearance being regulated by the diameter of the threads of the screw 200.

The oil in the valve chamber which enters through the passage 196 is exhausted through the passage 204 into the chamber 206 and out the passage 208 into the exhaust connection 186. The chamber 206 is in the form of a hole threaded at its upper end to receive the screw 210 which seals the upper end of the chamber 206 and acts as an abutment for the spring 212 which holds the ball valve 214 to its seat. The pressure of the spring 42 controls the oil pressure within the valve chamber.

As more clearly shown in Figs. 2 and 3 a collar 216 embraces the lower end 58 of the stem holder 56 and is removably affixed thereto in any suitable manner as, for example, by means of a pin 218. A manual knob 220 is provided for rotating the collar 216 and the stem holder 56 as a unit relative to the stem housing 32. Such rotation will result in the stem holder 56 being raised or lowered depending upon the direction of rotation due to its threaded connection at 222 with the lower end 58 and the housing 32. To limit the amount of rotation of the collar 216 to a partial revolution, an arcuate recess 224 is machined from the end thread of the housing 32 to provide shoulders 226 at the ends of the recess 224 with which a pin 228 carried upon the collar 216 will engage.

It will be appreciated that when the collar 216 is rotated in one direction the seat portion 68 acts upon the edge 70 to lift the stem 52 and move the valve spool 120 into its "up" position to raise the tool 16. When the operator wishes to lower the tool 16 into engagement with the work 23 rotation of the collar 216 in the opposite direction will enable the operator to cautiously approach the work with the tool. Thus, the collar 216 provides a conveniently located control means for raising and lowering the tool 16 relative to the work. When the tracer finger 18 is to engage and follow the template 20, the collar 216 will be rotated to remove the seat 68 from the edge 70 thus transferring the support of the tracer stem to the tracer finger 18.

I claim:

1. In a hydraulic duplicator attachment for machine tools and the like, a fluid control valve, means for actuating said valve comprising a tracer finger, an elongated axially movable stem carrying said finger, fixed port structure regulated by said valve, a housing for said stem, a seat carried by said housing at its lower end and having a central aperture through which said stem extends, an annular radially extending shoulder on said stem and engageable with said seat to support said stem, said stem housing having a reduced annular portion directly adjacent and above said seat defining a narrow closely fitted annular fulcrum for said stem and defining the pivotal plane of said stem, said stem having clearance with said housing above and below said plane for limited pivotal and axial action in all directions about said fulcrum.

2. In a hydraulic duplicator attachment for machine tools and the like, a fluid control valve, means for actuating said valve comprising a tracer finger, an elongated stem carrying said finger, a tubular housing for said stem, a narrow annular fulcrum for said stem located at the lower end of said housing which consists of a reduced annular portion with which said stem has a closely fitted axially slidable association, and a connection between

the upper end of said stem and said valve for transferring axial movement to said valve upon pivotal and axial movement of said stem.

3. In a hydraulic duplicator attachment for machine tools and the like as defined in claim 2 wherein said connection comprises a ball disposed between a pair of annular seats.

4. In a hydraulic duplicator attachment for machine tools and the like as defined in claim 2 wherein said stem 10 has an annular shoulder and said housing is provided with an annular seat directly adjacent said annular fulcrum upon which said shoulder is adapted to be supported.

5. In a hydraulic duplicator attachment for machine tools and the like as defined in claim 2 wherein said stem 15 has an annular shoulder and said housing is provided with an annular seat directly adjacent said annular fulcrum upon which said shoulder is adapted to be supported, that portion of said housing carrying said seat and fulcrum being axially adjustable to raise said stem and actuate said 20 valve.

6. In a hydraulic duplicator attachment for machine tools and the like, a lapped valve mechanism having opposite end portions for selectively controlling the flow of hydraulic fluid to opposite ends of an actuating cylinder upon minute movement of said valve structure, spring means for urging said valve structure in one direction, tracer mechanism for urging said valve structure in the opposite direction, and a hydraulic dampener for said valve structure to prevent chatter thereof comprising a closed hydraulic fluid circuit extending between the opposite ends of said valve structure with the latter functioning as a piston in said circuit and an adjustable restriction in said circuit for regulating the flow of hydraulic fluid therein.

7. In a hydraulic duplicator attachment for machine tools and the like, a lapped valve structure having opposite end portions for the regulation of the flow of fluid to opposite ends of a cylinder upon minute movement of said valve structure, spring means for urging said valve structure in one direction, tracer mechanism for urging said valve in an opposite direction, and a closed hydraulic circuit for obviating chatter of said valve structure under the influence of said tracer mechanism connecting the opposite ends of the cylinder in which said 45 valve functions as a piston and an adjustable restriction in said closed circuit for regulating the transfer of hydraulic fluid from one portion to the other thereof.

8. In a hydraulic duplicator attachment for machine tools, movable valve structure for regulating the direction of fluid flow to and from a hydraulic actuator, a tracer finger, a tracer stem structure connected between said finger and said valve structure for imparting the movement of said finger to said valve structure, an externally threaded stem housing concentrically encompassing said stem structure, mounting structure for said stem housing including a sleeve in which said stem housing is vertically slidably, and an internally threaded adjustment ring rotatably supported by said sleeve with which said stem housing is threaded for vertical adjustment of said stem housing in said sleeve upon rotation of 60 said ring.

9. In a hydraulic duplicator attachment for machine tools, valve structure comprising a movable valve spool, a sectional sleeve valve in which said spool is reciprocated, said sleeve valve being in the form of a pair of ported sections separated by a relatively thin spacer section, said ported sections having end walls spaced by said spacer portion, said spacer portion being in the form of a ring having radial teeth on the inner circumference thereof with portions between said teeth being inclined to the axis of said spacer portion and of sufficient length to provide passages radially extending between said end walls.

10. In a hydraulic duplicator attachment for machine tools, valve structure comprising a movable valve spool,

a tracer finger, stem structure imposed between said tracer finger and said spool valve for imparting the movement of said tracer finger to said spool valve, and a tracer-force transmitting cushion member imposed between said stem and said spool valve.
